US0D1024631S

(12) **United States Design Patent** (10) **Patent No.:** **US D1,024,631 S**
(45) **Date of Patent:** **** Apr. 30, 2024**

(54) **STAND**

(71) Applicant: **Nupur, LLC**, Baltimore, MD (US)
(72) Inventors: **Nupur Parekh Flynn**, Baltimore, MD (US); **Jennifer Ann Ewing**, Easton, MD (US); **Shannon Theresa Shingleton**, Arnold, MD (US); **Douglas Pemberton**, Timonium, MD (US); **Jeremy Asher Higgins**, Kansas City, MO (US)
(73) Assignee: **Nupur, LLC**, Baltimore, MD (US)

(**) Term: **15 Years**

(21) Appl. No.: **29/734,515**

(22) Filed: **May 13, 2020**

(51) LOC (14) Cl. **06-06**

(52) U.S. Cl.

USPC **D6/675.4**

(58) **Field of Classification Search**

(57) **CLAIM**

An ornamental design for a stand, as shown and described herein.

DESCRIPTION

FIG. 1 is a perspective view of a first embodiment.

FIG. 2 is a front view of a first embodiment.

FIG. 3 is a back view of a first embodiment.

FIG. 4 is a left side view of a first embodiment.

FIG. 5 is a right side view of a first embodiment.

FIG. 6 is a top side view of a first embodiment.

FIG. 7 is a bottom side view of a first embodiment; and,

FIG. 8 is a lower perspective view of a first embodiment. The broken lines in the drawings represent unclaimed subject matter and form no part of the claim.

1 Claim, 6 Drawing Sheets
